(57) **CLAIM**

The ornamental design for a ladder standoff, as shown and described.

DESCRIPTION

FIG. 1 is a perspective view of the ladder standoff;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof; and,

FIG. 8 is a perspective view thereof showing an example environment.

The broken lines in the figures depicting a ladder and a building façade are to show environment and form no part of the claimed design.

1 Claim, 6 Drawing Sheets

FIG. 1

FIG. 2

FIG. 3

FIG. 4**FIG. 5**

FIG. 6**FIG. 7**

FIG. 8
